2 SHEETS—SHEET 2.

UNITED STATES PATENT OFFICE.

CHARLES VOLNEY KERR, OF WELLSVILLE, NEW YORK, ASSIGNOR TO THE AMERICAN WELL WORKS, OF AURORA, ILLINOIS, A CORPORATION OF ILLINOIS.

SPEED-GOVERNOR.

1,233,276.

Specification of Letters Patent. Patented July 10, 1917.

Application filed March 23, 1914. Serial No. 826,541.

To all whom it may concern:

Be it known that I, CHARLES V. KERR, a citizen of the United States, residing at Wellsville, in the county of Allegany and 5 State of New York, have invented certain new and useful Improvements in Speed-Governors, of which the following is a specification.

This invention relates to new and useful 10 improvements in governors, and more particularly to that class designed for use in connection with elastic fluid turbines.

An object of this invention is to provide 15 a governor to be mounted on the rotary shaft of a turbine or the like in operative connection with the motive fluid controlling valve and to perform the usual functions of a governor by utilizing the centrifugal force at high speeds of leaf springs disposed 20 parallel to the shaft, thereby dispensing with the usual governor weights and avoiding the heavy pressures on pivots or knife edges due to the centrifugal force of such weights acting through levers upon the 25 usual governor springs.

Another object of this invention is the provision of mechanism for operatively connecting the governor with the governor valve for the purpose of reciprocating the 30 latter in a line parallel to that of the drive shaft of the turbine to which the said governor is applied.

A further object of this invention is to improve and simplify devices of this character, rendering them comparatively simple 35 and inexpensive to manufacture, reliable and efficient in use, and readily operated.

With the above and other objects in view, this invention resides in the novel features 40 of construction, formations, combinations, and arrangement of parts to be hereinafter more fully described and particularly pointed out in the appended claims.

In the drawings, in which similar reference characters indicate the same parts in the several figures,

Figure 1 is a longitudinal sectional view of my improved governor, taken on the line I—I of Fig. 2;

50 Fig. 2 is an end view of Fig. 1;

Fig. 3 is a transverse sectional view on an enlarged scale taken on the line III—III of Fig. 1;

Fig. 4 is a longitudinal sectional view

taken through the governor, on an enlarged 55 scale;

Fig. 5 is a transverse sectional view, taken on the line V—V of Fig. 1, on an enlarged scale; and

Fig. 6 is a diagrammatic view illustrating 60 the positions of the link connections between the governor and governor valve.

Referring to the accompanying two sheets of drawings, the numeral 1 designates in general the intake end of a turbine in which 65 is disposed the usual rotary drive shaft 2, which passes outwardly through the stuffing box 3 and bearing 4. The casing head of the turbine 1 is provided with the intake opening 5 which connects with the steam 70 chest 6, through the passage 7, said chest being in communication with the steam supply by the pipe 6'.

A sleeve 8 is suitably attached by a key or otherwise, to the shaft 2 within the bearing 75 4, and projects outwardly therefrom, terminating in a hood 9 rigidly connected to the shaft 2 through the medium of the sleeve 8, and rotatable therewith. The shaft 2, within this hood, is slightly reduced as at 10, and 80 slidable upon this reduced portion is a sleeve 11 provided with terminal peripheral flanges 12, 12, disposed inwardly to engage the shaft, thereby spacing the major portion of the sleeve from said shaft, and obviously reducing friction.

The end of the shaft 2 is bifurcated, as at 13, and formed with a recess 14, designed to receive the terminal point of a pin 15 disposed within said bifurcated end 13. A 90 lateral pin 16 passes through the outer end of the slidable or movable sleeve 11 and inner end of the pin 15, connecting the same rotatably to the shaft 2. The outer end of the pin 15 passes through a recess 17 in the 95 pivot block 18 and rotates against the adjustable bearing block 19, threaded in said block 18. From this construction it will be readily seen that the pin 15 moves longitudinally in axial alinement with the shaft 2 100 upon movement of the sleeve 11.

A collar 20 is formed upon the inner end of the sleeve 11 while a corresponding collar 21 is keyed, as at 22, to the outer end of the shaft 2 at the open end of the hood 105 9. The collar 21 is further held against any undesired movement by the lock nut 23. The peripheries of the collars 20 and

21 are notched to receive the laminated or leaf springs 24, each of which comprises a bundle of thin strips of suitable metal disposed parallel to the shaft 2, and held in position by the locking rings 25 which are placed over the collars 20 and 21 and retained thereon by any suitable means. By this construction any one or more of the springs may be removed and stronger or weaker springs substituted therefor, if found necessary, or should any of the springs become broken or injured, they may be readily taken out and new ones put in their place.

15 It will also be seen, the said springs 24 not only form the retractile means of the usual form of the governor but at the same time also perform the same function as weights for actuating the governor.

20 An oil cup 26 is attached to the pivot block 18 and communicates with the recess 17 from which the oil or other lubricant will pass through the passages 27 (see Fig. 3) in the pin 15 to lubricate the various operating parts.

25 Outwardly extending arms 28 project from the steam chest 6 and support a bearing 29 in which an operating rod 30 is slidably located. This rod 30 is in alinement with the stem 31 of the valve 32 disposed within the steam chest 6 for reciprocating movement in a line parallel to the axis of the shaft 2. The valve 32 is flexibly attached to the stem 31 and slides in a sleeve 32' of the same material as the valve 32, said sleeve 32' being held in place by the cover of the steam chest 6. The stem 31 operates through a sleeve 33 secured rigidly to the head of the steam chest, while attached to this sleeve and adjustable thereon is a collar 34 arranged to seat one end of a tensioning spring 35, the opposite end of which is supported by the collar 36 carried by the above mentioned rod 30, which latter at this point is attached to the valve stem 31.

30 A second pair of collars 37, 37 are adjustable upon the rod 30 and support a yoke 38, to the opposite sides of which are pivoted the links 39, 39 which are in turn pivoted to the upwardly extending links 40, 40. These links 39 and 40 are pivotally connected at their intermediate points to the links 41 and 42, which are pivoted at their opposite ends to the arms 28, as indicated by the number 43. These links 39, 40, 41 and 42 form a pantograph, as shown in Fig. 6, by which if the outer end of the pin 15 or block 18 is moved in a straight line, the lower ends of the links 39 and yoke 38, will

35 move in a line parallel thereto; consequently when the pivot block 18 is moved in a line parallel to the axis of the shaft 2, the yoke 38 will be moved in a line parallel to the axis of the shaft 2 and also parallel to the axis of the valve stem 31, manifestly recip-

rocating the valve 32 in its proper line of operation. This action of the links 39, 40, 41 and 42 will follow as clearly indicated in the line diagram illustrated in Fig. 6, which shows the positions of the pantograph and consequently if points A, B and C are in a straight line, and point B is fixed, if A is moved to A', D will move to D', E to E', F to F', and C to C', and therefore line C—C' is a straight line parallel to the line A—A', for the reason that the triangles A B E, and A C D, are similar, and the figure B E D F, is a parallelogram. This form of construction of levers or links makes it possible to reach around a corner, as it were, to attach a centrifugal governor to a controlling valve.

40 The collars 37 have a slight clearance, which overcomes any alinement troubles. A change of speed while running can be effected by adjusting the collars or lock nuts 37. Spring tension in the spring 35 varies inversely with turbine load and combines with steam pressure on stem 31 which varies directly with the load to form a practically constant pressure on the governor connections to take up back-lash or lost motion. It will be noted that in operation one cutoff edge of the valve 32 reaches its seat earlier than the other, which gives better control of light loads.

45 The operation of the device is as follows:

50 At high speed the combined weight and springs 24 are bowed outwardly as indicated by the dotted lines of Fig. 4, and may touch the hood 9. This movement of the springs 24 forces the sleeve 11 outwardly carrying with it the pin 15 and pivot block 18, thereby operating the valve 32 through the medium of the links 39, 40, 41 and 42 to change the speed to the desired degree.

55 For moderate speeds, or when small speed variation with the change of load is desired, removable weights 44, as indicated in dotted lines in Fig. 4, can be attached to the springs 24.

60 Obviously, this invention uses the centrifugal force of the springs which increases with the square of the speed. The power or resistance of the combined weight and springs increases with the number and thickness of the springs 24 which are employed. Deflection of said springs 24 varies with the fourth power of the length of the leaf springs, and inversely with the square of the thickness of the leaf of each spring. A great elasticity of design is thus secured, and pivots under high pressures are entirely avoided.

65 From the foregoing disclosures, taken in connection with the accompanying drawings, it will be manifest that a governor such as described is provided, which will fulfill all the necessary requirements of such a device, it being understood that various minor

changes in the specific details of construction can be resorted to within the scope of the appended claims without departing from, or sacrificing any of, the advantages of the invention.

What I claim is:—

1. A governor for turbines or the like, comprising a rotary shaft, a centrifugal governor on and rotating with said shaft, a motive fluid controlling valve, and a series of links forming a parallel motion connecting said governor and valve for moving the valve in a line parallel to the axis of the rotary shaft.
- 15 2. A governor for turbines or the like, comprising a rotary shaft, a centrifugal governor on and rotating with said shaft, a motive fluid controlling valve, a member longitudinally slidable on the shaft and connected to the governor, and a series of links arranged and connected with the slidable member and the valve for moving said valve in a line parallel to the axis of the rotary shaft.
- 20 3. A governor for turbines or the like, comprising a rotary shaft, a centrifugal governor on and rotating with said shaft, a motive fluid controlling valve, a member longitudinally slidable on the shaft and connected to the governor, a pivot block con-

nected to and moving with the longitudinally slidable member, and a series of links arranged in the form of a pantograph connected with the pivot block and the valve for moving said valve on a line parallel to the axis of the rotary shaft.

35

4. A governor for turbines or the like, comprising a rotary shaft, a centrifugal governor on and rotating with said shaft, a motive fluid controlling valve, an operating rod connected with the controlling valve, a yoke connected to the operating rod, a member longitudinally slidable on the shaft and connected to the governor, a pivot block connected to and moving with the longitudinally slidable member, links connected to the pivot block and yoke and to each other, a fixed support, links pivoted to said support and at intermediate portions of the first mentioned links whereby said valve is moved on a line parallel to the axis of the rotary shaft.
